UNITED STATES PATENT OFFICE.

HERBERT E. KEELER, OF NEW YORK, N. Y.

DESIGN FOR A SCREW.

SPECIFICATION forming part of Design No. 32,924, dated July 10, 1900.

Application filed June 12, 1900. Serial No. 20,081. Term of patent 9½ years.

To all whom it may concern:

Be it known that I, HERBERT E. KEELER, a citizen of the United States, and a resident of the city of New York, borough of Manhattan, in the county and State of New York, have invented and produced a new and original Design for a Screw, of which the following is a full, clear and exact description.

Reference is to be had to the accompanying drawings, forming a part of this specification, in which similar characters of reference indicate corresponding parts in both the views.

Figure 1 is a perspective view of a screw, showing my design; and Fig. 2 is a plan view of the same.

The leading feature of the design consists in the configuration of the screw made the subject of the accompanying illustrations.

The design in its entirety consists of the

semispherical head A and the shank B, having the cylindrical smooth portion C and the tapering portion D, the said head having diametrical slots E and F standing approximately at right angles to one another, the slot E extending in depth to within a short distance of the base of the head A, while the slot F extends completely through the head and diametrically through the smooth portion C of the shank B.

Having thus fully described my invention, I claim as new and desire to secure by Letters Patent—

The design for a screw, as herein shown and described.

HERBERT E. KEELER.
